DRILLING ATTACHMENT FOR RIVETING MACHINES

Frank A. Boyle, San Diego, Calif., assignor to
 Consolidated Vultee Aircraft Corporation, San
 Diego, Calif., a corporation of Delaware

Application October 4, 1949, Serial No. 119,469

8 Claims. (Cl. 29—26)

1

This invention relates to riveting machines of the type adapted to form an opening in a work piece, introduce a rivet into this opening and thereafter set the rivet, the work piece being maintained in the same position during these various operations.

It is a conventional practice in certain industries, such as airplane manufacturing, which are required to rivet metal sheets or work pieces, particularly sheets or work pieces of aluminum and aluminum alloys, to employ automatic punching and riveting machine. With the development of the trend toward higher speed airplanes, which embody heavier and heavier skins, the combined thicknesses of parts to be riveted reach a point where the automatic punching and riveting machines cannot effectively and efficiently perform their function. It is therefore generally the object of this invention to provide an attachment for an automatic riveting machine which will adapt it for use with work pieces having relatively greater combined thicknesses than were formerly encountered. The attachment will further adapt the machine for perforating and riveting material, such as steel, which normally is too thick and heavy to punch by conventional means.

The invention has for a principal object the provision, in a riveting machine of the character above described, of an improved form of drilling attachment for making the rivet receiving hole in the work piece.

Another object of the invention is to provide improved control means for automatically halting the operation of the drill attachment after the formation of a rivet receiving hole.

The invention further contemplates for use a pilot pin which is movable into the perforation, after the drilling means has withdrawn therefrom, to maintain the individual parts of the work piece in position for the performance of the riveting operation.

Another object of the invention resides in the provision of a novel drive system for effecting operation of the drill attachment.

Still another object of the invention lies in providing automatically operative means associated with the drill attachment to provide a current of air for cleaning the drilled openings of dust and chips created by the drill.

Another object of the invention is to provide a drilling attachment having an improved form of gage device for determining the depth of the perforation made by the cutting tool.

A further object of the invention is to pro-

2

vide in a machine of the character described an improved holding attachment adapted during the drilling operation to press the juxtaposed work pieces firmly into engagement with one another to prevent metal particles from sifting between the workpieces while the drill is acting upon them.

Another object of the invention is to provide a drilling attachment which is generally of new and improved construction, may be manufactured at a comparatively low cost and effectively and efficiently fulfills its intended purpose.

Other objects and features of the present invention will be readily apparent to those skilled in the art from the following specification and appended drawings wherein is illustrated a preferred form of the invention, and in which:

Figure 1 is a general perspective view of a riveting machine embodying the drilling attachment in accordance with the present invention;

Figure 2 is an enlarged fragmentary view, in side elevation, showing the drilling attachment in operative position;

Figure 3 is an enlarged fragmentary view, but in front elevation, showing the drilling attachment in operative position;

Figure 4 is a perspective view of the stop assembly for the air cylinder piston;

Figure 5 is a perspective view of the cutting tool;

Figure 6 is a perspective view of the gaging means for the drilling attachment;

Figure 7 is a side elevational view of the drill assembly unit and the associated electric switch assembly which determines when the drilling operation is to stop;

Figure 8 is a top view of the drilling unit alone;

Figure 17 is a fragmental perspective view of the clamping arm.

The drilling attachment of the present invention is contemplated for use with those machines which are adapted automatically to insert rivets in perforations formed in the material to be riveted and to complete the riveting operation by heading the rivets. Embodied in such machines is a reciprocating pressure plunger-rivet set which will be operative during both the perforating and riveting operation to assist in the performance of these operations.

The automatic riveting machine employed may be of any well known construction, such as the Erci Automatic Punching and Riveting Machine, Model 1002 made by the Engineering and Research Corporation of Riverdale, Maryland, and embodying the principles of U. S. Patents 1,990,998 and 2,056,559. The punch or perforating mechanism of the above machine will be supplanted by the drilling attachment of the present invention. Since it is understood that this machine is to be regarded merely as illustrative of the type of machine with which the drilling attachment of this invention may be used the machine will therefore be described only with such particularity as is necessary to an understanding of the invention.

An automatic riveting machine of the type above mentioned, is shown in the drawings and is there designated generally by the numeral 10. This machine 10 is adapted to perform, sequentially, a series of operations, namely, perforating the work to be riveted, automatically feeding rivets into the perforations formed and then heading the rivets, and the machine 10 will perform these various operations without there being any movement of the work between operations.

The riveting machine 10 normally comprises a generally C-shaped yoke or frame 11 of relatively massive size supported in up-right position by an integral base or pedestal portion 12. The yoke 11 comprises vertically spaced apart arms or jaws 13 and 14, which jaws are of substantial length to effect a long work receiving throat in order that work pieces of considerable width may be accommodated by the machine 10.

To the upper yoke jaw 13 is suitably affixed a drilling mechanism 15, a rivet holding assembly 16 and a reciprocating pressure applying shaft or plunger 17, which elements accomplish the operations of perforating the work piece and of feeding the rivets into the perforations. The lower jaw 14 mounts an anvil assembly 18 which is operative to support the work piece and to effect heading of the rivets inserted into the perforations.

The drilling mechanism 15 comprises a drilling unit 21 supported by a swinging arm 22 which is secured, at its upper end, to a rotatable and reciprocable shaft 23 suitably mounted in yoke jaw 13. The rivet holding assembly 16, positioned adjacent the drilling unit 21, is of conventional construction and comprises a usual rivet shoe 24 carried by a swingable support member or arm 25 which in turn is mounted, at its upper end, on a rotatable and reciprocable shaft 26 suitably supported by upper jaw 13. The rivet shoe 24 serves to support rivets therein, which are re-

ceived from a rivet tube 27 and to deposit such rivets in perforations made in the work piece by the drilling unit 21. The swingable supporting arms 22 and 25 are suitably mounted in upper jaw 13 of machine 10 and are controlled by suitable mechanisms embodied therein so as to present the drilling unit 21 and the rivet shoe 24 in alternate sequence below the reciprocating plunger 17 for cooperation therewith. The drilling unit 21 and the rivet supporting shoe 24 are adapted to move pivotally and in unison on the completion of each perforating and each riveting operation. The means and mechanism provided by machine 10 for mounting the shafts 23 and 26 to the upper jaw 13 and for effecting their simultaneous rotative movement to move the drilling unit 21 and the rivet shoe 24 in unison are conventional and well known to those skilled in the art and there is no need, therefore, for a particularized description to be made of such means and mechanism.

Figures 2 and 3 show the drilling unit 21 located in operative position upon a work piece 28, being held thereupon under the pressure of the plunger 17. The plunger 17 is suitably mounted in upper jaw 13 of machine 10 so as to have a reciprocating movement. In such movement plunger 17 is adapted to engage and carry the drill unit 21 downwardly toward the work piece, in a manner hereinafter to be more fully described, and maintain it thereupon until the drilling operation is completed. Thereafter the plunger 17 is re-treated and the drilling unit 21 returns to the position of Figure 1, after which the supporting arm 22 for the drilling unit 21 and the supporting arm 25 carrying the rivet shoe 24 swing or rotate in unison and exchange places beneath the plunger 17. Rivet shoe 24 is then in position to be engaged by plunger 17, in its next longitudinal movement, to be carried thereby to the work piece 28 to cause a rivet to be inserted into the hole formed for its reception by drilling unit 21, the plunger 17, acting as a rivet set, maintains pressure on the rivet until it is headed upon the anvil assembly 18. After the riveting operation the plunger 17 and the rivet shoe 24 both return to their upper position and the machine is then ready for the drilling unit 21 to be swung beneath the plunger 17 to begin the next series of operations. The purpose of the reciprocating plunger 17 thus is to assist in the performance of both the drilling operation and the rivet inserting and rivet heading operation.

For actuation of the reciprocating plunger 17 there is provided a usual air cylinder 31 mounted on the upper jaw 13. The air cylinder 31 contains a reciprocable piston 32 adapted to be moved downwardly by air under pressure introduced through a port (not shown) into the air cylinder above the piston 32. A piston rod 33 is connected to piston 32 and extends to either side thereof. The portion 34 of the piston rod 33 which extends downwardly from piston 32 projects out of the lower end of the cylinder 31 and is adapted to have the plunger 17 suitably secured to it. A spring 35 located within the cylinder above the piston 32 is suitably connected to the upwardly extending portion 36 of piston rod 33 and is adapted to be compressed upon the downward movement of the piston 32. Spring 35 expands, on release of the air pressure applied to piston 32, to return the piston 32 to its rest position and carry the plunger 17 upwardly with it and thereby relieve the pressure being applied to the drilling unit 21 or the

rivet shoe 24, whichever happens to be in engagement with plunger 17. The support arm 22 for the drilling unit 21 and the support arm 25 carrying the rivet shoe 24 are each adapted normally to occupy a position vertically spaced from the anvil assembly 18 and the work resting thereupon. Usual spring means, not shown, are provided within upper yoke jaw 13 for cooperation with the reciprocating shafts 23 and 26 which respectively carry the support arms 22 and 25. These spring means continually exert their bias to maintain the shafts 23 and 26 in their upper position so that movement of the support arms 22 and 25 downwardly by the plunger 17 will be accomplished against the force of these spring means. When plunger 17 is withdrawn by piston 32 the support arms 22 and 25 are moved upwardly by the shafts 23 and 26 which automatically are returned to their upper position under the bias of their cooperating return spring means.

Introduction of air under pressure to the air cylinder 31 and sequencing actuation of the drilling unit support arm 22 and the rivet shoe support arm 25 are controlled, in usual manner, remotely from a conventional foot operated control member 37, which embodies a plurality of air valves (not shown) actuated individually by a number of foot pedals 39. The foot operated control member 37, through its pedal actuated air valves, governs the feeding of compressed air received from an outside source of supply (not shown) through an air lead 38 to effect the operation of the drilling unit 15, the rivet supporting assembly 16 and the reciprocating plunger 17. A pair of air leads 41 and 42 connect the foot operated control member 37 and a conventional shift cylinder assembly 43 which affords the power for operation of the air cylinder 31. The shift cylinder assembly 43 is adapted to operate a conventional cable and pulley arrangement 44 to actuate appropriate linkage (not shown) which will effect rotative movement of shafts 23 and 26 to pivot the drilling unit 21 and rivet shoe 24 so that, alternately, each occupies a position directly beneath reciprocating plunger 17 to enable movement thereby.

An air lead 45 channels air from the main air lead 38 to suitable mechanism, hereinafter to be described, which operates the drill unit 21. Suitable connections are provided between air lead 45 and a usual regulator valve 46 and a usual master control valve 47 for feeding air to these valves. The regulator valve 46 provides air under desired pressure to the anvil assembly 18 for use thereby in the support of the work piece. The master control valve 47 connects through air lead 50 to the air cylinder 31 to provide the power for operation of the piston 32 and to exhaust the air from cylinder 31. The pulley and cable arrangement 44 through linkage, now shown, controls the operation of the master control valve 47 to determine the periods and speed of feeding and of exhausting air from air cylinder 31 during the drilling and rivet setting operations.

It is here particularly emphasized that the details of construction of the air cylinder 31, the support arms 22 and 25, the structure for effecting rotation of these arms, the main control valve 47, the regulator valve 46, the shift cylinder assembly 43, the foot operated control member 37, and the arrangement and operation of such elements form no part of the present invention. These elements are the principal

standard working parts of a commercially available automatic riveting machine. Since the machine employed herein is well known to those skilled in the art it is not necessary to describe it in any further detail than has been done for a ready understanding of its construction and operation.

The drill unit 21, in accordance with the present invention, comprises, as best shown in Figures 7, 8 and 9, a composite gear housing 51 formed of upper and lower body portions 52 and 53, which are secured one to the other by screws 54. Each of the body portions 52 and 53 are provided with a plurality of recesses 55 formed in a row therein; the recesses 55 of upper body portion 52 are adapted to align with the recesses 55 of the lower body portion 53 when the body portion 52 and 53 are joined to one another to form a series of three longitudinally spaced gear chambers 56, 57 and 58 with the center chamber 57 having intercommunication with the end chambers 56 and 58.

A gear train 59 is provided within housing 51 and comprises a drive gear 61 which meshes with an idler gear 62 which in turn meshes with a driving gear 63. The drive gear 61 is located within gear chamber 56 and is secured to or formed integral with shaft 64, which shaft is journaled at each end by being mounted in spaced ball bearing journals 65 and 66 provided in chamber 56. The idler gear 62 is disposed in gear chamber 57 and is secured to or formed integral with a shaft 67. A pair of spaced roller bearings 68 and 69 in chamber 57 journal the shaft 67. The driving gear 63 is positioned in the third gear chamber 58 and also is secured to or formed integral with a shaft 71. Shaft 71 is mounted for rotative movement by being journaled in ball bearing journals 72 and 73 disposed on either side of driving gear 63 and located in gear chamber 58.

Shaft 71 for driving gear 63 has one end thereof extending through an opening in the base of lower body portion 53 and is externally threaded at this end as indicated at 74. A cutting tool 75 is adapted to be secured to the shaft 71 for actuation thereby. This cutting tool 75 may be of any selected type, diameter and length and for purpose of illustration of this invention is herein shown as a combination countersink and drill member. This member 75 is positioned below driving gear 63 and in axial alignment with shaft 71 and comprises a cylindrical shank 76 having at one end an internally threaded bore 77 and at the opposite end a conical countersinking portion 78 comprising an annular series of equidistantly spaced downwardly and inwardly inclined cutting edges 79, and projecting below and from the countersinking portion 78 is a drilling portion 81 having generally longitudinally extending cutting edges 82.

The externally threaded end 74 of shaft 71 is received within internally threaded bore 77 to connect the combination countersink and drill member 75 to the gear train 59 to be powered thereby.

A gaging means 83 is provided for determining the depth of the hole and the depth of the countersink made by the cutting tool 75. This gaging means 83 comprises an internally threaded ring 84 having its upper end 85 castellated to provide an annular series of equidistantly spaced upstanding teeth 86. A cylindrical helical spring 87 having a diameter greater than that of ring 84 is secured, as by welding, at one end to the

ring 84. The opposite end of the spring 87 is welded to the periphery of a perforated annular plate or washer member 83 and positions the latter so that the opening 89 therethrough is disposed axially aligned with cutting tool 75 to permit the passage of the cutting edges thereof. The washer 88 is adapted to lie upon the upper surface of the work piece in surrounding relationship to the area thereof which is to be perforated and is of value in preventing marring or scratching of the skin surface by drill chips created in the drilling operation. The cylindrical spring 87 also has a tendency to prevent the drill chips from flying freely about. The coils of the spring 87 present themselves in the path of the drill chips and will block or hinder the passage of most of the chips and confine them to the area defined by the diameter of the spring 87. Two pairs of diametrically opposed projections 91 extend from the lower end 92 of the ring 84 toward the washer 88 and, upon downward movement of housing 51, are engageable with the upper surface thereof to constitute stop means which assist in determining the advance to be made by the cutting tool 75 in the perforating operation, as will be described.

Operative connection of the gaging means 83, to the gear housing 51 is afforded by an externally threaded annular flange or collar portion 93 provided depending from lower body portion 53 and encircling the cutting tool 75. Ring 84 by reason of its threaded engagement with collar 93 can be axially moved thereupon in either direction to adjust the position of gaging means 83 relative to the cutting tool 75 and thereby determine the amount of movement available to the cutting tool 75. The outer periphery of the ring 84 is preferably knurled for ready gripping and easy manual movement. A leaf spring 94, secured at one end, as by welding, to the exterior surface of lower body portion 53 projects therefrom to position its free end 95 between two adjacent upstanding teeth 86 so that teeth 86 and free spring end 95 cooperate to effect an indexing means. The leaf spring 94 exerts its bias to hold the free end 95 thereof normally between two teeth with sufficient force that the ring 84 will be effectively maintained in the desired adjusted position on collar 93 and inadvertent movement thereof is avoided. Manual rotation of the ring 84 to change the amount of advance of the cutting tool 75 will force the free spring end 95 out from between its rest between adjacent teeth and when the ring 84 has been adjusted to a desired position the spring end 95 will snap into position between a pair of teeth to lock the ring 84 in place.

The drill unit 21 is held in operative position on machine 10 by the swingable supporting arm 22. The supporting arm 22 is formed with a compression collar 96 at its lower end which is adapted to fit over and encircle an annular flange 97 upwardly extending from upper body portion 52 of gear housing 51. A screw, not shown, is provided on the compression collar 96 to effect tightening thereof upon the flange 97 whereby the housing 51 is rigidly affixed to supporting arm 22. An externally threaded adapter 98 is removably fitted into a threaded bore 99 provided in annular flange 97 and lies in axial alignment with cutting tool 75. The adapter 98 has a recess 101 in its upper end which receives the end of the reciprocating plunger-rivet set 17 which carries the drill unit 21 into operative position upon the work piece. The entrance to

the recess 101 is chamfered, as shown, for easy access of plunger 17. The adapter 98 serves, in addition to connecting the plunger 17 and the drill unit 21 for common movement, to maintain concentricity and alignment of the cutting tool 75 and the locating device of the anvil assembly 18, to be described.

To drive the cutting tool 75 there is provided an air motor 102 operatively connected to the gear train 59 through a drive shaft assembly 103. The drive shaft assembly 103 comprises a tubular member 104 into which is telescoped, for slidable movement, a rod element 105. The tubular member 104 is connected to a rotatable drive shaft 106 provided by the air motor 102 by means of a universal joint 107 whereby rotative movement can be provided to the drive shaft assembly 103. The rod element 105 is joined to the gear train 59 through the medium of a second universal joint 108, as best shown in Figure 9. The universal joint 108 comprises a body portion 109, suitably secured to the end of rod 105, having spaced, downwardly extending arm portions 111. A second body portion 112, having an internally threaded socket 113 provided therein and spaced upstanding arm portions 114 at its upper end which lie disposed adjacent the arm portions 111 and at right angles thereto. A pivot pin 115 is carried by spaced arms 114 and extends therebetween. A second pivot pin 116 supported by the spaced arms 111 is adapted to extend through an opening (not shown) in the pivot pin 115 to effect thereby a pivotal connection between the two body portions 109 and 112. A spacer 117, formed of metallic material such as steel, is disposed in the area between the pairs of spaced arms 111 and 114. The pivot pins 115 and 116 are passed through spacer 117 which serves to prevent slippage between the pins.

One end of shaft 64 of drive gear 61 extends through an opening in the top of upper body portion 52 and carries external threads thereon, as indicated at 118. This threaded end 118 is adapted to fit into internally threaded socket 113 to complete the connection between the drive shaft assembly 103 and the gear train 59. Universal joint 107 embodies a similar pivotal arrangement as is incorporated in universal joint 108 and effects an operative connection between the tubular member 104 and the rotatable air motor drive shaft 106 to provide rotative movement of the drive shaft assembly 103. This rotative movement of drive shaft assembly 103 causes shaft 64 to rotate to drive its gear 61, which actuates idler gear 62, the latter in turn actuating driving gear 63 to rotate the cutting tool 75, carried by shaft 71, to enable it to perform the perforating operation when brought to the work piece.

The air motor 102 which actuates drive shaft assembly 103 is of conventional construction, and comprises, as best shown in Figure 10, a casing 121 having a usual air vane assembly 122 suitably supported therein for rotative movement when air under pressure is introduced into the casing 121. The air vane assembly 122 is suitably connected through a usual reduction gear arrangement 123 to actuate the drive shaft 106 which is connected by universal joint 107 to the drive shaft assembly 103. A valve assembly 124, best illustrated in Figure 10, is provided for controlling the feeding of air to the casing 121 to run air motor 102. Valve assembly 124 comprises a housing 125 affixed

to the exterior of casing 121 as by welding, with communication between the interior of housing 121 and housing 125 being afforded by a tubular member 126. An adapter 127 is threaded into the top wall of housing 125, extends the length thereof, and has a longitudinal air passage 128 provided therein. Passageways 131 interconnect the air passage 128 with the interior of housing 125. A ball bearing valve 132 is confined for movement in air passage 128 and is adapted to seat on a shoulder 133 formed adjacent the lower end of air passage 128 to close communication between air passage 128 and the interior of housing 125. An L-shaped fitting 134 is threaded into the upper end of air passage 128 and connects through an air lead 135 to air line 45 to provide the air needed for operation of the air motor 102. Pressure of the air conducted by air lead 135 to air passage 128 acts to hold the ball bearing valve 132 normally in seated position on its cooperating shoulder 133. To move valve 132 to unseated position to establish free passage of the air to the air motor 102 there is afforded a valve pin 136 slidably mounted in the lower end of adapter 127 with its upper end normally positioned below and spaced from the ball bearing valve 132 and its opposite end projected to the exterior of valve housing 125 and resting upon the upper end of an actuating reciprocable plunger 137 slidably positioned within a vertical bore 138 formed in a mounting bracket 141. A threaded fitting 142 is located in the lower end of bore 138 and is connected to an air lead 143 whereby air pressure may be applied to the bottom of actuating plunger 137 to effect longitudinal movement upwardly of the plunger 137 to actuate valve pin 136 to unseat valve 132. The detailed construction of air motor 102 and valve assembly 124 constitutes no part of the present invention and the construction illustrated in the drawings is understood only to be representative of valve controlled air powered devices that could be employed in this invention.

The air motor 102 is supported in operative position on machine 10 by the mounting bracket 141 which is affixed to the outer wall of the air cylinder 31 by a plurality of suitable fasteners 139. The mounting bracket 141 is provided adjacent its one end 140 with a vertical bore 144 into which a portion of the casing 121 of air motor 102 is tightly fitted to mount the air motor 102 in operative position. Horizontally spaced from bore 144 is the vertical bore 138 in which is slidably mounted the longitudinally movable actuating plunger 137 which moves valve pin 136. The opposite end 145 of the mounting bracket 141 is adapted to accommodate a valve arrangement 146. Valve arrangement 146 comprises an adapter 147 having a threaded engagement with the defining walls of the upper end of a vertical bore 148 formed in the mounting bracket 141. The adapter 147 extends from the top to the bottom of bracket 141 and is provided with a longitudinal bore 151 communicating by way of passages 152 with bore 148.

A fitting assembly 153 is mounted in the upper end of longitudinal bore 151 and is connected through an air lead 154 with the air lead 45 to provide a path whereby air may be conducted to bore 151. The fitting assembly 153 includes a usual pet cock 155 which permits closure of the air passage through the fitting assembly 153 when desired. A ball bearing valve 156 is disposed for movement within longitudinal bore 151 and has

a valve seat 157 formed in the bore 151 adjacent the passages 152. The pressure of the air introduced within longitudinal bore 151 is adapted normally to position the valve 156 in its seated position to prevent air passing from bore 151 through passages 152 into vertical bore 148. A valve pin 158 is slidably positioned at the lower end of adapter 147 and is movable into engagement with valve 156 to effect unseating thereof. Movement of valve pin 158 is effected and controlled by a cam actuator 161 to be described. With valve 156 in open position air will freely pass into vertical bore 148 from which it escapes by way of a usual hose fitting 162. Hose fitting 162, as best seen in Figure 2, is located at end 145 of mounting bracket 141. It is adapted to communicate with bore 148 through a port (not shown) in the wall of the mounting bracket. A T-coupling 163 connects hose fitting 162 to the air lead 143, which air lead effects operation of the actuating plunger 137 for valve assembly 124. The T-coupling 163 also connects to the one end of an air lead 164 whose opposite end is fitted to a tubular element 165 mounted on and projecting laterally from upper body portion 52 of gear housing 51. As seen in Figure 8, the tubular element 165 is disposed on body portion 52 so as to locate the bore 166 thereof aligned with the entrance to an arcuate passage 167. This passage 167 empties by way of a connecting passage 168 into the space defined by the interior wall surfaces of annular flange 93, which flange 93 depends from lower body portion 53. The air provided to this space is adapted to be directed at the area of the work-piece being drilled by cutting tool 75 and serves to blow the chips formed in the perforating operation away from the tool 75. It is here noted that when air is passed by valve 156 to the hose fitting 162, such air is directed simultaneously to both the air leads 143 and 164. The purpose of air lead 143 is to provide the pressure necessary to move actuating plunger 137 upwardly to unseat valve 132 thereby to discharge air into casing 121 of air motor 102, for the operation of its air vanes 122 to rotate drive shaft assembly 103 and thereby actuate cutting tool 75. The air fed through the second air conduit 164 will play upon cutting tool 75 throughout its period of drilling operation and until valve pin 158 permits re-seating of valve 156 to block further passing of air to the two air lines 143 and 164.

As described hereinbefore the air cylinder 31 through reciprocal movement of its piston 32 effects reciprocal movement of the plunger 17. Plunger 17 is adapted to bottom in recess 101 of adapter 98 to move the drilling unit 21 to the work-piece. Washer 88 provided by gaging means 83 of drilling unit 21 will contact the work-piece first and rotating cutting tool 75 will follow, passing through the central opening 89 in washer 88 to perforate the work piece. The gaging means 83 determines the depth of the opening and of the countersink to be formed in the work piece. Engagement of the washer 88 by the opposed pairs of legs 91 projecting from the lower end of ring 84 determines the amount of advance of the cutting tool 75 into the work-piece. For with this engagement any further movement of the housing 51 carrying the cutting tool 75 in the direction of the work piece is halted. Application of excessive downwardly directed pressure by piston 32 and plunger 17 upon housing 51 of drilling unit 21 after the depending legs 91 have contacted the washer 88

is prevented by the provision of a piston stop assembly 169 operatively supported within the air cylinder 31. Piston stop assembly 169, as best seen in Figure 4, comprises a pivotally mounted plate member 170 movable between a horizontal, or inactive position, and a vertical, or piston stopping, position. Piston 32 when forced down by air pressure is adapted to engage with the upraised plate member 170 whereupon its further downward movement is prevented. A reciprocating linkage assembly 171 is operatively connected to the pivotal plate member 170 for effecting movement thereof. The reciprocating linkage assembly 171 is operated by a rotatable shaft 172 which is driven by an actuator assembly 173 to be described. However, even though its advance is stopped, the cutting tool 75 will continue to rotate. To conclude this rotating action of the cutting tool 75 and to return the drilling unit 21 to inoperative position there is provided a conventional self-contained, normally open, snap switch assembly 174, of the micro-switch type. The switch assembly 174 is mounted upon an extension 175 of the upper body portion 52 of housing 51. The casing of switch assembly 174 is provided with an externally threaded projection 176 which is fitted through an opening 177 in extension 175 and receives a nut 178 which serves to fasten the switch assembly 174 securely to the housing 51. An actuator 179 provided for operating switch assembly 174 projects below extension 175 and carries an elongated supporting member 181 transversely disposed and underlying extension 175. Elongated member 181 mounts a stud 182 which is threaded therethrough, and which has its shank 183 disposed for free slidable movement within an opening 184 in extension 175 and has its lower end 185 disposed spaced from the transverse elongated member 181. It is seen that as housing 51 of the drilling unit 21 is carried toward the work piece the switch assembly 174 supported by it and the upstanding stud 182 supported by the switch actuator 179 are also moved in the same direction. This movement will bring the lower end 185 of the stud 182 into engagement with the surface of the work piece. Stud 182 will thereupon exert force upon the transverse member 181 to move it upwardly away from the surface of the work piece. This movement will be transmitted to the switch actuator 179 to cause it to move to operate switch 174. Switch 174 is suitably electrically connected to electric means, not shown, associated with the shift cylinder assembly 43 to cause it to function so as to bleed the main control valve 47 and exhaust air cylinder 31, whereupon piston 32 is returned to its rest position under the bias of compression spring 35, and plunger 17 withdraws from the adapter 98. With release of the pressure of plunger 17 therefrom the drilling unit 21 will be carried upwardly away from the work piece by support arm 22 and its shaft 23, the shaft 23 moving upwardly under spring bias. Stud 182 by reason of its threaded connection with extension 175 can be readily rotated to adjust the position of its lower end 185 and thus change the time of actuation of switch 174 as desired.

The shift cylinder assembly 43 functions also to operate the cam actuator 161, as will be described in further detail, to cause valve 156 to close and disconnect the air lead 164 from the air supply whereupon the air motor 102 ceases to function and the cutting tool 75 stops rotating.

As stated hereinbefore valve 156 which con-

trols the feeding of air used to drive air motor 102 and to blow chips away from the cutting tool 75 is itself controlled by a cam actuator 161, whose construction is best illustrated in Figures 12 and 13. Cam actuator 161 comprises a generally U-shaped member 186 comprising spaced legs 187 and having an outwardly projecting generally arcuate portion 188 located adjacent the bight 189 thereof. The projecting portion 188 has an inclined surface 191 formed thereon upon which the lower end of valve pin 158 rests. It is apparent that as cam actuator 161 is oscillated to shift the position of inclined surface 191 relative to the valve pin 158 the latter is made to ride up and down this inclined surface and will be given a reciprocating movement toward and away the ball bearing valve 156. Pin 158 will displace valve 156 from its seat 157 when raised high enough to engage valve 156, and will permit valve 156 to assume its seated position when the inclined surface 191 moves in a direction to permit pin 158 to fall in its bore to lie spaced from the valve 156.

Oscillating movement of cam actuator 161 to effect reciprocation of valve pin 158 is obtained through an elongated member 192, a portion of which lies disposed between the legs 187 of cam actuator 161 and is secured thereto by a number of studs 193. The elongated member 192 is pivotally joined, at its end 194 by a pivot pin 195 to a clevis 196 provided at the exterior end of a reciprocating connecting rod 197. The connecting rod 197 is suitably attached to the pulley and cable arrangement 44 controlled by the shaft cylinder assembly 43 and through which cable and pulley arrangement 44 reciprocating action of the connecting rod 197 is obtained.

Adjacent embraced end 198 of the elongated member 192 is provided an opening 199 into which is tightly fitted the lower end 200 of the shaft 172. Shaft 172, as stated hereinbefore, is operatively connected to the reciprocating linkage assembly 171 in air cylinder 31 to actuate piston stop plate member 170 between its horizontal and vertical positions.

Provided substantially centrally in elongated member 192 is a second opening 201 into which is adapted to project the free end 202 of an oscillating member 203, whose opposite end is suitably rotatably mounted. Free end 202 fitting into opening 201 effects a pivotal connection between elongated member 192 and oscillating member 203. With the construction described the elongated member 192 upon having its end 194 actuated by reciprocating rod 197 will, through its opposite end 198, rotate shaft 172 to operate reciprocating linkage 171 to raise and lower the piston stop plate member 170 and will oscillate cam actuator 161 to shift the position of inclined surface 191 on cam actuator 161 to effect reciprocating movement of valve pin 158. The movement of valve pin 158 riding on cam actuator 161 is coordinated with the movement of the piston stop plate member 170 by means of elongated member 192 and cam actuator 161. Valve pin 158 will be actuated by inclined surface 191 of cam actuator 161 into valve opening position as shaft 172 affixed to cam actuator 161 rotates to operate reciprocating linkage 171 to raise plate member 170 into piston stopping position, and valve pin 158 will rest in its inactive position on inclined surface 191 at the time that plate member 170 assumes a horizontal position.

In the formation of rivet holes by drilling in metal sheets brought adjacent one another there

exists a likelihood that dust particles and fine chips created by the drill may sift between the sheets and hold the adjacent surfaces thereof out of contact with one another and thereby tend to prevent the obtainment of a fully effective riveted joint. The present invention provides an attachment for use with machine 10 which functions to maintain the work parts in desired close engagement as they are being perforated and riveted. This attachment comprises, as best illustrated in Figures 16 and 17, a hold-down assembly 205 which includes an elongated clamping member 206 bent to effect an obtuse angle defined by a portion 207 inclined to a portion 208. The inclined portion 207 is pivotally connected, at its end 209, by a pivot pin 211, to a bracket 212 which is securely fastened by studs 213 to the underface of yoke jaw 13. To effect pivotal movement of clamping member 206 there is provided a conventional air cylinder 214 which is mounted upon the underface of yoke jaw 13 by studs 215. The air cylinder 214 includes a usual reciprocable piston (not shown) which actuates a piston rod 216, the end of which projects from the bottom of the air cylinder 214. The piston rod 216 has a lost motion connection with portion 208 of the clamping member 206, which lost motion connection is effected by a stud 217 whose shank is passed through a slotted opening 218, provided in portion 208 of elongated member 206, and threaded into the bottom end of piston rod 216. An air conduit 220, connected at one end to air cylinder 214 and at the other to air lead 41, provides the power for operation of air cylinder 214 to move the piston rod 216 to actuate the clamping member 206 and press portion 208 thereof tightly against the upper surface of the work to hold the two adjacent pieces of material comprising the work in firm engagement during the perforating and riveting operations. The hold down assembly 205 is located adjacent plunger 17 and is movable in the same plane as is plunger 17 to clamp the work piece in the area immediately surrounding the spot to be perforated and riveted.

Portion 208 of pivoted clamping member 206 has its outer end 209 formed generally into a U-shape comprising two legs 221 and 222 spaced apart, with leg 221 being of a smaller length than opposite leg 222. Clamping member 206 projects legs 221 and 222, to lie disposed on opposite sides of plunger 17. These legs 221 and 222 lie positioned on opposite sides of the cutting tool 75 and its associated gage means 83 when the drilling unit 21 is moved into position for engagement and actuation by plunger 17. The disparity in length of legs 221 and 222 is necessary to prevent interference with the swinging movement of the drilling unit 21 to and from its position beneath plunger 17. The projection of shorter leg 221 would lie in the path of movement of cutting tool 75. Having a shorter length provided for leg 221 permits the drilling unit 21 to swing freely past the end thereof. Rivet shoe 24 is normally so positioned that it lies disposed above the longer leg 222 and therefore when swinging into and out of position for cooperation with plunger 17 it passes over leg 222 without interference being offered to its freedom of movement by leg 222.

The air cylinder 214 is provided with a laterally projecting flange 223 adjacent its lower end. An adjusting stud 224 is threaded into flange 223 and extends to either side thereof. Stud 224 carries a lock nut 225 on one side to fix the position of the stud 224, and has one end adapted to en-

gage portion 208 of clamping member 206. The stud 224 permits adjustment of the position of portion 208 relative to air cylinder 214.

The anvil assembly 18 supports the work piece 28 as it is being perforated and riveted. It is of conventional construction, and, as seen in Figure 14, comprises a frame 226 carrying a usual anvil support 227. The anvil support 227 mounts a reciprocable generally U-shaped stripper saddle member 228 having spaced legs 229 and 230 which are disposed within cylinders 231, shown in dotted outline, provided by frame 226 and anvil support 227. Air is provided to these cylinders 231 by a lead 232 extending from regulator valve 46. This air is adapted to act upon the bottom surfaces of legs 229 and 230 to move the stripper saddle member 228 into its upper position as shown in Figure 14.

An air lead 233 is connected at one end, as illustrated in Figure 15, to bight 234 of the stripper saddle member 228 to provide air to a chamber 235 located in the bight 234, which air is used for blowing away drill chips formed during the perforating operation as will be further described. Air lead 233 is connected at its other end to air lead 44 from which it obtains the air which is supplied to chamber 235.

An anvil post 236 is suitably mounted by anvil support 227 and projects upwardly therefrom to extend into a bore 237 provided in a reciprocably movable work supporting stripper member 238 to guide the latter in its movements and to serve to head the rivets. Stripper member 238 rests its lower end 239 upon the top of stripper saddle member 228 and is bodily movable therewith relative to anvil post 236 during the riveting operation. The purpose of the stripper is to support the work piece as it is being operated upon. It will hold the work piece spaced from the top of anvil post 236 in order that the shank of a rivet may extend through the work prior to being headed. Air pressure normally is continuously provided by regulator valve 46 through air lead 232 to the cylinders 231 to act on legs 229 and 230 of the stripper saddle 228 to raise the stripper member 238 to the position shown in Figure 14 to hold it in proper relationship to the drilling unit 21 and rivet shoe 24. In the performance of the riveting operation the pressure provided upon the upper surface of work piece 28 by rivet shoe 24 and top set or plunger 17 will cause the stripper member 238 to move downwardly and relative to the anvil post 236.

Stripper member 238 has a vertical bore 242 provided therein which connects its upper surface with air chamber 235 whereby air can be led from the chamber 235 to exit at the bottom of the work piece rested on stripper member 238 to blow away any drill chips which appear upon the work supporting stripper member 238. Slidably positioned within a through bore 244 in anvil post 236 and extending downwardly into an aligned bore 245 in anvil support 227 is a locating pin member 246, a slidably movable adapter 253 upon the upper end of which pin member 246 rests, and a stop member 251 having a bore 250 therein. A spring 247 is disposed within stop member bore 250 and acts upon the lower end of locating pin member 246, exerting its bias thereupon, normally to project the upper end 248 thereof above the top of anvil post 236 and above the stripper member 238. The upper end 248 of pin member 246 will lie spaced from the top of anvil post 236 and stripper member 238 until engaged and forced downwardly either by the under surface of

a work piece or by the end of a rivet shank. The locating pin member 246 is positioned and held by anvil post 236 in axial alignment with cutting tool 75 and therefore, after the completion of a drilling operation and the withdrawal of the cutting tool 75 from the rivet hole formed thereby, the locating pin 246 will be moved upwardly by its spring 247 to extend into the rivet hole and thereby hold the perforated work piece in position until a rivet shank is inserted into the rivet hole by the plunger operated rivet shoe 24. The rivet shank will press the locating pin member 246 downwardly until the top of the pin member 246 lies in the plane of the top of anvil post 236, at which point a shoulder 249 on the adapter 253 engages the upper end of stop member 252 to halt further longitudinal downward movement of locating pin 246. Pin 246 then cooperates with anvil post 236 to effect an anvil upon which the rivet shank is headed as additional pressure is applied to the head of the rivet by plunger 17.

The anvil assembly 18 may be bodily raised to and lowered from its operative position by a mechanism, not shown, housed within frame 226, which mechanism is operated by air pressure provided through air leads 252 and controlled by appropriate pedals 39 on foot operated control member 31. Provision is made for raising and lowering the anvil assembly 18 to more readily permit placement of a work piece in proper position between the yoke jaws.

In the operation of the invention a work piece 28 will be placed upon the stripper member 238 of anvil assembly 18 to rest it in position for perforation and riveting. A pedal 39 on the foot operated member 31 is then actuated to by-pass air from air supply conduit 38 to the air lead 41. This air actuates the shift cylinder assembly 43, which in turn actuates the cable and pulley arrangement 44. The cable and pulley arrangement 44 operates the master control valve 47 to pass air from air conduit 45 through air line 50 into the air cylinder 31 to build up pressure therein to effect downward movement of piston 32 against the bias of spring 35.

The operation of cable and pulley arrangement 44 withdraws reciprocating rod 197 into the upper jaw 13. Clevis 196 on the end of reciprocating rod 197 thereupon moves end 194 of elongated member 192 to effect rotative or arcuate movement of the opposite end 198 thereof about the connection of free end 202 of oscillating member 203 and the elongated member 192. This movement of end 198 will rotate shaft 172 to operate the linkage assembly 171 to raise the piston stop assembly 169 provided within air cylinder 31. The arcuate movement of end 198 of elongated member 192 will also move the cam actuator 161 to displace its inclined surface 191 relative to the valve pin 158 to cause the latter to ride up this inclined surface 191 and thereby move upwardly within bore 151 of valve adapter 147 to engage ball bearing valve 156 to unseat it. The unseating of valve 156 allows air to pass from lead 154 and lead 45 through the passages 152 to issue through hose fitting 162. From hose fitting 162 this air takes two paths, along one path it is conducted by air lead 164 to the gear housing 51 to discharge through communicating passages 166, 167 and 168 into the space defined by annular flange 93 whereby a blast of air is provided at the cutting tool 75. The second path from the hose fitting 162 is by way of the air lead 143 which connects to hose fitting 142 and

discharges against the bottom surface of reciprocable plunger 137 to apply pressure thereagainst for moving it upwardly, longitudinally, within its bore 138. Upward movement of plunger 137 will move valve pin 136 in the same direction to bring the latter into engagement with ball bearing valve 132 to move valve 132 off its seat 133. Valve 132 controls the feeding of air required for operation of the air motor 102. This air is taken from air supply line 38 by way of air leads 45 and 135 and is passed to bore 128 in adapter 127. Unseating of valve 132 by valve pin 136 allows the air to flow from bore 128 through passages 131 and tubular member 126 to act upon vane assembly 122 to effect rotation thereof. Vane assembly 122 drives shaft 166 which in turn rotates drive shaft assembly 103. Rotation of drive shaft assembly 103 will actuate gear train 59 to rotate the cutting tool 75. Thus the movement of cam actuator 161 to actuate valve pin 158 results in the actuation of air motor 102 to effect rotation of cutting tool 75 and in the provision of an air blast at the cutting tool 75.

As the pressure in air cylinder 31 builds up the piston 32 is moved downwardly to move plunger 17 into engagement with adapter 98 carried by gear housing 51 of drilling unit 21. Continued downward movement of plunger 17 moves the drilling unit 21 toward the work piece 28 to bring the cutting tool 75 upon the work piece 28. The time required to build up the necessary pressure within air cylinder 31 to move piston 32 and plunger 17 to perform their function is such that the cutting tool 75 is rotating at its maximum speed before the work piece is contacted. This obviously results in a more efficient cutting operation and applies less strain to the operating elements. Also before the cutting tool 75 begins the cutting operation the hold-down assembly 205 will have operated to apply a clamping pressure upon the upper surface of the work piece 28. When air is admitted to line 41 to actuate shift cylinder assembly 46 it will also enter air line 220 which is connected to line 41. Air line 220 will pass this air to air cylinder 214 of the hold-down assembly 205. On introduction of air into air cylinder 214 its piston rod 216 is actuated downwardly to effect pivotal movement of clamping member 206 to carry the U-shaped end of portion 208 into engagement with the upper surface of work piece 28. The pressure applied by clamping member 206 will efficiently hold the adjacent parts comprising the work piece tightly in engagement prior to and during the drilling operation.

After the cutting tool 75 has cut an opening and counter-sink in the work piece 28 to the depth determined by the gage means 83 the lower end 185 of stud 182 engages the upper surface of the work piece 28 to effect upward movement of switch actuator 179 to operate the normally open snap switch 174. Switch 174 on being operated actuates the shift cylinder assembly 43 to exhaust it and cause it to act through the cable and pulley arrangement 44 to bleed the master control valve 47 to exhaust air cylinder 31 to permit the return of piston 32 to its upper position. Upward movement of piston 32 withdraws plunger 17 from engagement with drilling unit 21. Upon release of the pressure of plunger 17 shaft 23, which mounts support arm 22 and drilling unit 21, moves upwardly in the same direction as plunger 17 to space drilling unit 21 above the work piece 28. This upward movement of drilling unit 21 withdraws cutting tool

15 from the rivet hole cut by it. As cutting tool 75 withdraws from the rivet hole the upper end 248 of locating pin member 246 is projected into the rivet hole to hold the work piece in position for the riveting operation. Exhausting the shift cylinder assembly 43 will effect exhausting of air cylinder 214 of hold-down assembly 205 through air line 220. Piston rod 216 will withdraw into air cylinder 214 to rotate clamping member 206 away from the work piece 28 and release it from clamping pressure. The perforating operation is now complete.

In the riveting operation a pedal 39 on the foot controlled member 36 is pressed to feed air through line 42 to again actuate the shift cylinder assembly 43 which again operates the cable and pulley arrangement 44. Cable and pulley arrangement 44 actuates the appropriate linkage for effecting pivotal movement, in unison, of the support arms 22 and 25 to provide a substitution in position of the drilling unit 21 and the rivet shoe 24, moving drilling unit 21 out from under plunger 17 and replacing it with rivet shoe 24.

Reciprocating connecting rod 197 will be projected forwardly to move clevis 196 and rotate the end 198 of elongated member 192 about the connection of elongated member 192 with the free end 202 of oscillating member 203. Rotative movement causes rotation of shaft 172 which operates linkage assembly 171 to move piston stop plate member 169 to its lowered position. Rotative movement of end 198 of elongated member 192 also moves the cam actuator 161 to displace its inclined surface 191 relative to the valve pin 158 to cause the latter to fall so as to disengage from ball bearing valve 156. Valve 156 will then be moved by air pressure, provided through air leads 45 and 154, to rest on valve seat 157 and thereby cut off the air supply to hose fitting 162. Air leads 143 and 164 connected to hose fitting 162 will then be shut off. With air lead 143 closed off there is no pressure available to hold plunger 137 in its upper position. Plunger 137 will therefore fall downwardly and valve pin 136 actuated by plunger 137 will move in the same direction to disengage the ball bearing valve 132. Valve 132 will be moved by air pressure to seat on shoulder 133 to discontinue the feeding of air from air lines 135 and 45 to the air motor 102. Air motor 102 will then cease to function and rotation of drive shaft assembly 103 will be halted. Gear train 59 will stop and the cutting tool 75 will come to rest. With no air being provided to hose fitting 162 the air blast provided at the cutting tool 75 through air lead 164 is discontinued.

The cable and pulley arrangement 44 actuated by shift cylinder assembly 46 operates main valve 47 to pass air to the air cylinder 31 to effect movement of piston 32 therein. Plunger 17 will be moved by piston 32 to engage rivet shoe 24 to carry it, and the rivet disposed therein, to the work piece to dispose the shank of the rivet in the rivet hole formed in the drilling operation. Plunger 17 and piston 32 will continue their downward movement under the force of the pressure built up in air cylinder 31 until the shank of the rivet is headed by the anvil assembly 18. After the riveting operation the removal of pressure from the last actuated foot pedal 39 on foot operated control member 37 shuts off air to shift cylinder assembly 43. Shift cylinder assembly 43 will then bleed and effect actuation of the cable and pulley arrangement 44 to operate main

control valve 47 to bleed it and effect exhaustion of the air from air cylinder 31 to return plunger 17 to its neutral position and disengage it from the rivet shoe 24. The work piece 28 is then shifted to a new position on anvil assembly 18 and the drilling and riveting cycle above described is repeated.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What I claim is:

1. In a riveting machine having a pair of mutually opposed jaws with a work piece supporting anvil assembly mounted upon one jaw and a drilling assembly and a rivet holding member, each supported for swinging movement upon the opposite jaw adapted to be alternately positioned over said anvil assembly and alternately movable into engagement with a work piece to be perforated and riveted, said drilling assembly comprising a rotary cutting tool and drive means operatively connected to said rotary cutting tool for rotating it, clamping means operatively mounted on said jaw which supports said drilling assembly and said rivet holding member adapted to move toward the anvil assembly supporting jaw to contact and press upon the work piece prior to and during perforation thereof by the rotary cutting tool, said clamping means comprising an elongated member having one end pivotally secured to the jaw supporting the drilling assembly, an air cylinder having a piston movable toward and away from the work piece, and means effecting a lost motion connection between the piston and said elongated member whereby said elongated member is movable to the work piece to bring its free end into clamping engagement therewith, and a locating pin member slidably supported by said anvil assembly adapted to move into an opening cut into the work piece upon withdrawal of the rotary cutting tool and the elongated member therefrom.

2. In a riveting machine having a frame with a pair of spaced apart arms, a work piece supporting assembly provided upon one arm, a drilling attachment movably mounted on the opposed arm adapted to be advanced and retracted relative to a work piece to be perforated, said drilling attachment comprising a housing, a cutting tool rotatively supported by said housing, a gear train carried by said housing operatively connected to said cutting tool for rotating it, means for actuating said gear train to rotate said cutting tool before its engagement with a work piece, said means comprising motor driven means having a connection with the gear train for actuation thereof, gage means supported in association with said housing and operative to determine the depth of perforation of the work piece by the cutting tool, said gage means comprising a ring member movably mounted on said housing in encircling relationship to the cutting tool, and means for providing an air blast at the cutting tool effective to blow away dust particles created by the cutting tool in perforating the work piece, said means comprising a tubular member supported by said housing having a connection with a source of air supply, said housing having passages therein interconnecting said tubular element and the area defined by the ring member, into which area air may be passed to act on the

area of the work piece being perforated by the cutting tool.

3. In a riveting machine having a pair of mutually opposed jaws, one disposed above the other, with a work piece supporting assembly mounted upon the lower jaw and a drilling assembly and a rivet holding member movably supported in association with the upper jaw, said drilling assembly and rivet holding member adapted alternately to advance to and withdraw from a work piece to be perforated and riveted, said drilling assembly comprising a housing, a cutting tool rotatively supported by said housing, and a gear train carried by said housing operatively connected to said cutting tool for rotating it, a motor mounted on said upper jaw, a drive shaft assembly operatively interconnecting said motor and said gear train, means for operating said motor to effect actuation of said drive shaft assembly and said gear train prior to said cutting tool engaging the work piece, said drive shaft assembly comprising telescopic means, a universal joint connecting one end of said telescopic means to said motor, and a second universal joint connecting the opposite end of said telescopic means to said gear train, and clamping means operatively mounted on the upper jaw adapted to contact and press upon the work piece prior to perforation thereof by the cutting tool.

4. In a riveting machine having a frame with a pair of spaced arms, one disposed above the other, with a work piece supporting assembly mounted upon the lower arm and a drilling assembly and a rivet holding member movably supported in association with the upper arm, said drilling assembly and rivet holding member adapted alternately to advance to and withdraw from a work piece to be perforated and riveted, said drilling assembly comprising a housing, a cutting tool rotatively supported by said housing, a gear train carried by said housing operatively connected to said cutting tool for rotating it and means for providing an air blast at the cutting tool effective to blow away dust particles created by the cutting tool in perforating the work piece, said means comprising an air lead-in member supported by the housing adapted to communicate with passages provided by said housing, which passages direct air to the area of the work piece being perforated by the cutting tool, an air motor mounted on said upper jaw, a drive shaft assembly operatively interconnecting said air motor and said gear train, valve means for controlling the feeding of air to said air blast means and to said air motor, means for actuating said valve means to feed air to said air motor to effect operation of said cutting tool prior to its engaging the work piece, and clamping means operatively mounted on the upper jaw adapted to contact and press upon the work piece prior to perforation thereof by the cutting tool.

5. In a riveting machine having a pair of mutually opposed jaws, one disposed above the other, with a work piece supporting assembly mounted upon the lower jaw and a drilling assembly and a rivet holding member movably supported in association with the upper jaw, said drilling assembly and rivet holding member adapted alternately to advance into and withdraw from a work piece to be perforated and riveted, said drilling assembly comprising a housing, a cutting tool rotatively supported by said housing, a gear train carried by said housing operatively connected to said cutting tool for rotating it, and means for providing an air blast

at the cutting tool effective to blow away dust particles created by the cutting tool in perforating the work piece, said means comprising an air lead-in member supported by the housing adapted to communicate with passages provided by said housing, which passages direct air to the area of the work piece being perforated by the cutting tool, an air motor mounted on said upper jaw, a drive shaft assembly operatively interconnecting said motor and said gear train for actuating said gear train prior to said cutting tool engaging the work piece, said drive shaft assembly comprising telescopic means, a universal joint connecting one end of said telescopic means to said motor, and a second universal joint connecting the opposite end of said telescopic means to said gear train, valve means mounted on said frame for controlling the feeding of air to said air blast means and to said air motor, means for actuating said valve means to feed air to said air motor to effect operation of said cutting tool prior to its engaging the work piece, and clamping means operatively mounted on the upper jaw adapted to contact and press upon the work piece prior to perforation thereof by the cutting tool.

6. In a riveting machine having a frame with a pair of spaced apart arms, one disposed above the other, a work piece supporting assembly provided upon the lower arm, a drilling attachment movably mounted on the upper arm adapted to be advanced and retracted relative to a work piece to be perforated, said drilling attachment comprising a housing, a cutting tool rotatively supported by said housing, a gear train carried by said housing operatively connected to said cutting tool for rotating it, means for actuating said gear train to rotate said cutting tool before its engagement with a work piece, said means comprising motor driven means having a connection with the gear train for actuation thereof, gage means supported in association with said housing and operative to determine the depth of perforation of the work piece by the cutting tool, said gage means comprising a ring member movably mounted on said housing in encircling relationship to the cutting tool, means for providing an air blast at the cutting tool effective to blow away dust particles created by the cutting tool in perforating the work piece, said means comprising an air lead-in member supported by the housing, said housing having passages therein interconnecting said air lead-in member and the area defined by the ring member, into which area air may be passed to act upon the area of the work piece being perforated by the cutting tool, and clamping means operatively mounted on the upper arm adapted to contact and press upon the work piece prior to perforation thereof by the cutting tool.

7. In a riveting machine having a pair of mutually opposed jaws, one disposed above the other, with a work piece supporting assembly mounted upon the lower jaw and a drilling assembly and a rivet holding member movably supported in association with the upper jaw, said drilling assembly and rivet holding member adapted alternately to advance to and withdraw from a work piece to be perforated and riveted, said drilling assembly comprising a housing, a cutting tool rotatively supported by said housing, a gear train carried by said housing operatively connected to said cutting tool for rotating it, gage means supported in association with said housing and operative to determine the depth of perforation of the work piece by the cutting tool,

said gage means comprising a ring member movably mounted on said housing in encircling relationship to the cutting tool, means for providing an air blast at the cutting tool effective to blow away dust particles created by the cutting tool in perforating the work piece, said means comprising an air lead-in member supported by the housing, said housing having passages therein interconnecting said air lead-in member and the space defined by the ring member, into which space air may be passed to act upon the area of the work piece being perforated by the cutting tool, an air motor mounted on said upper jaw, a drive shaft assembly operatively interconnecting said motor and said gear train, valve means for controlling the feeding of air to said air blast means and to said air motor, means for actuating said valve means to feed air to said air motor to effect operation of said cutting tool prior to its engaging the work piece, and clamping means operatively mounted on the upper jaw adapted to contact and press upon the work piece prior to perforation thereof by the cutting tool.

8. In a riveting machine having a pair of mutually opposed jaws, one disposed above the other, with a work piece supporting assembly mounted upon the lower jaw and a drilling assembly and a rivet holding member movably supported in association with the upper jaw, said drilling assembly and rivet holding member adapted alternately to advance to and withdraw from a work piece to be perforated and riveted, said drilling assembly comprising a housing, a cutting tool rotatively supported by said housing, a gear train carried by said housing operatively connected to said cutting tool for rotating it, gage means supported in association with said housing and operative to determine the depth of perforation of the work piece by the cutting tool, said gage means comprising a ring member movably mounted on said housing in encircling relationship to the cutting tool, means for providing an air blast at the cutting tool effective to blow away dust particles created by the cutting

tool in perforating the work piece, said means comprising an air lead-in member supported by the housing, said housing having passages therein interconnecting said air lead-in member and the space defined by the ring member, into which space air may be passed to act upon the area of the work piece being perforated by the cutting tool, an air motor mounted on said upper jaw, a drive shaft assembly operatively interconnecting said motor and said gear train, said drive shaft assembly comprising telescopic means, a universal joint connecting one end of said telescopic means to said motor, and a second universal joint connecting the opposite end of said telescopic means to said gear train, valve means for controlling the feeding of air to said air blast means and to said air motor, means for actuating said valve means to feed air to said air motor to effect operation of said cutting tool prior to its engaging the work piece, and clamping means operatively mounted on the upper jaw adapted to provide a clamping pressure upon the work piece prior to perforation thereof by the cutting tool, said clamping means comprising an air cylinder having a piston movable toward and away from the work piece, an elongated member having one end pivoted to said upper jaw, and means interconnecting said elongated member and said piston whereby said elongated member is movable to the work piece to bring its free end into clamping engagement therewith.
